CIGARETTE VENDING MACHINE

Walter E. Moore, Bel-Nor, Mo., assignor to Universal Match Corporation, St. Louis, Mo., a corporation of Delaware

Filed May 4, 1964, Ser. No. 79,798

Term of patent 14 years

(Cl. D52—3)

FIG. 1.

FIG. 3.

FIG. 2.

FIG. 4.

FIG. 1 is a top plan view of a cigarette vending machine, showing my new design;

FIG. 2 is a front elevation;

FIG. 3 is a side elevation; and

FIG. 4 is a perspective view of the machine.

The rear of the vending machine is substantially flat and plain in appearance.

I claim:

The ornamental design for a cigarette vending machine, substantially as shown and described.
